CLAIM

The ornamental design for a table, as shown and described.

DESCRIPTION

FIG. 1 is a perspective view of a table showing my new design;

FIG. 2 is an enlarged scale view of the top of the leg
shown in FIG. 1;

FIG. 3 is an enlarged scale view of the skirt shown in FIG. 1; and

FIG. 4 is a top plan view thereof.

The opposite two sides not shown in FIG. 1 are identical thereto.

FIG. 1

FIG. 2FIG. 3FIG. 4
